OPEN-END SOCKET WRENCH

Allen J. Brame, Los Angeles, Calif., assignor to
 Tubing Appliance Company, Inc., Los Angeles,
 Calif., a corporation of California

Application October 8, 1952, Serial No. 313,726

3 Claims. (Cl. 81—58.2)

1

This invention relates to open-end socket wrenches, and consists more particularly in new and useful improvements in ratchet operated socket wrenches of the general type shown and described in the patent to Fish No. 2,578,687, designed to facilitate use in difficult applications such as to encircle tubing, conduit, cable, shafting and the like in close quarters where wrenches of ordinary construction cannot satisfactorily be employed.

An object of the present invention is to provide an improved wrench head, basically similar to that of the open-end pipe wrench shown and described in my copending application Serial No. 300,260, filed July 22, 1952, and particularly adapted to suit the structural requirements of a socket wrench of the type above referred to.

Thus, it is a further object of the invention to provide in a socket wrench, a head comprising a pair of stampings which, when superimposed, form the walls of a housing for the socket receptor and the co-acting elements of the pawl and ratchet mechanisms.

Another object of the invention is to provide an improved head for socket wrenches which can be fabricated and assembled at a cost far less than that of ordinary socket wrenches, while at the same time combining maximum strength and adaptability with minimum overall dimensions for accomplishment of the desired purposes herein referred to.

A still further object of the invention is to provide a ratchet operated socket wrench having a head structure formed of a pair of substantially identical stampings which form the housing for the operative parts of the wrench and are designed to provide supporting and guiding trackways for the rotatable hub which receives the shank of the wrench socket.

With the above and other objects in view which will appear as the description proceeds, the invention consists in the novel features herein set forth, illustrated in the accompanying drawings and more particularly pointed out in the appended claims.

Referring to the drawings in which numerals of like character designate similar parts throughout the several views:

Figure 1 is a view in side elevation showing the assembled wrench with a socket element inserted from its upper side and the operating handle in place;

Figure 2 is a top plan view of the wrench head shown in Figure 1;

Figure 3 is a similar view from the underside of the wrench;

2

Figure 4 is an enlarged plan view of the wrench head shown in Figure 3, with the top cover partly broken away to illustrate the interior of the wrench head, and with the socket omitted;

Figure 5 is a sectional view taken on the line 5—5 of Fig. 4;

Figure 6 is a sectional view taken on line 6—6 of Fig. 4;

Figure 7 is a sectional view taken on line 7—7 of Fig. 4;

Figure 8 is a top plan view of a slightly modified wrench head structure; and

Figure 9 is a sectional view taken on line 9—9 of Fig. 8.

In the drawings, the wrench head is generally designated by the numeral 10, and, as shown in Figure 5 for example, one form thereof consists of a pair of identical superimposed stampings 11 and 12, of substantially oval shape, in plan profile, as seen in Figures 2 and 3. The stampings 11 and 12 are provided at one end with longitudinally extending registering slots which when the stampings are assembled, form a mouth 13 which opens into a circular hub receiving portion 14 which extends transversely through the two stampings.

As seen in Figure 5 each stamping is provided around its convex outer edge with a right angularly disposed flange 15, which, when the stampings are assembled, jointly form the side wall of a housing. The proper assembly of the stampings may be facilitated by the provision of a pair of complementary and inter-engaging index fingers 15a, Figure 1, such as those shown in my said co-pending application No. 300,260, arranged to seek cooperative engagement in orienting the stampings during assembly.

Within the housing formed by the stampings 11 and 12, there is provided a spacer block 16, consisting of a series of metal laminations shaped to fit closely within the confines of the housing and of a similar plan profile. The laminations of the spacer block are transversely drilled at suitable points and provided with bushings 17 as best seen in Figure 6, for receiving connecting pins or rivets 18 which pass through and secure the stampings 11 and 12.

The main web of each stamping is formed with openings to receive the rivets 18 and the defining edges of the openings are dimpled as at 19, the opposed dimples of respective stampings extending inwardly of the housing to be received by the corresponding ends of the bushing passageways in the laminations of the spacer block 16. The bushings 17 are of such a length that the opposite end faces of the same are engaged by the inner

extremities of respective dimples 19, when the stampings are secured together by the rivets 18.

As in the case of the other wrenches above referred to, the central portion at one side of the head 10 is provided with a square opening 20 which extends through the stampings 11 and 12 and the spacer block 16 for receiving the square end of an operating tool or handle 21 as shown in Figs. 1 to 3.

The circular hub receiving portion 14 of the head 10 is adapted to rotatably embrace a hub or ratchet wheel 22 shown in Fig. 4, formed with a slot 23, adapted to register with the slot 13 comprising the open mouth of the wrench head. The peripheral edge of hub 22 is transversely reduced in thickness and provided with a series of transverse notch-like grooves and teeth 24 which extend circumferentially around the entire unslotted periphery of the hub and are adapted to fit between the overlying inner edges of the opposed stampings 11 and 12 as shown in Fig. 6. The registering concave edges of the laminations of spacer block 16 are inset with respect to the corresponding edges of the stampings 11 and 12, to provide an annular recess for receiving the peripheral teeth 24 of the hub 22.

In the form of the invention shown in Figs. 5 to 7, the concave inner edges of the stampings 11 and 12 are turned inwardly at right angles as at 25, to form opposed circular guide ribs which fit in complementary grooves or trackways 26 in the opposed faces of the hub 22, which define the inner limits of the reduced tooth portion of the hub and serve to rotatably support the hub 22 between the opposed stampings 11 and 12.

As seen in Fig. 4, the series of ratchet teeth 24 which substantially bound the hub 22, co-act with a pair of pawls 27 which are pivotally mounted in suitable recesses 28, formed in the inset, concave face of the block 16, adjacent the periphery of the hub 22. These pawls are normally urged into engagement with the teeth 24 by means of springs 29, the pitch of the teeth being such as to clear the pawls upon relative rotation of the hub and the head in one direction and to operatively engage the pawls when relative rotation occurs in the opposite direction. The central portion of the hub 22 is cut out as at 30 to form a semi-circular socket receptor into which the slot 23 opens.

The annular concave face of the socket receptor preferably terminates in substantially hook-shaped driving shoulders 31 and 32, and provides a transverse recess for the slidable reception of a complementary shank 33 of any selected work-engaging member such as the socket 34 shown in Figs. 2 and 3. The shank 33 has a cut-out portion which terminates at each side in angularly disposed abutments 35 and 36 which form driven faces for engagement with the hook-shaped shoulders 31 and 32 respectively. Thus upon rotation of the hub 22 in either direction, the shank 33 of the socket is positively rotated therewith.

The central portion of the concave face of the socket receptor 30 is transversely drilled to receive a spring-pressed ball 37 for engaging a complementary recess in the shank of the socket so as to lock the latter against displacement in the socket receptor.

Turning now to the modified form of housing shown in Figs. 8 and 9, it will be seen that instead of providing a pair of opposed guide ribs and grooves for rotatably supporting the hub within the housing, I may provide only one inturned

flange 38 for rotatably engaging a complementary annular recess 39 in the reduced peripheral edge of the hub 22. This single guide arrangement is preferably arranged in the lower stamping 12 as seen in Fig. 9, and the corresponding inner edge of stamping 11 extends straight inwardly as at 40, where it abuts the shoulder of the hub 22 and overlies the upper edges of the peripheral teeth 24. For certain uses a wrench of this type, having only the single set of guide groove and rib, is perfectly satisfactory, as the engagement of the guide rib and groove on one side, coupled with the complementary fit of the edge of the stamping 11 in the reduced peripheral edge of the hub 22, affords sufficient lateral support for the rotatable hub.

It is believed that the use of my improved wrench will be apparent to those skilled in the art, but it may be briefly stated that the slots 13 and 23 in the housing and hub respectively are first aligned as shown in Fig. 4 and the shank 33 of a selected socket is inserted. The handle 21 is then inserted with its squared end in the squared opening 20 and movement of the handle in either clockwise or counter-clockwise direction, depending upon the arrangement of the teeth 24 with respect to the pawls 27, causes the rotation of the hub 22. Rotation of the hub causes a driving engagement between the respective hooked shoulders 31 or 32 with the abutting driven faces 35, 36, of the shank of the hub.

As in the case of my said co-pending application, a wrench head formed of opposed stampings and the laminated spacer block interposed therebetween and designed to accommodate the socket element, provides a decided improvement over wrenches heretofore known in this general category. The dimples 19 formed in the stampings 11 and 12 engage the block 16 carrying the pawls, and support the loads set up in the use of the wrench, through the webs of the stampings. In other words, the dimples 19 transfer into the block 16 shear forces created when a torsional movement is applied to the hub 22 in the use of the wrench. This is so for the hub 22 is supported in all rotative positions through the complementary flange and groove constructions shown. The means used to secure the stampings 11 and 12 in assembled position are thus not subject to any shear loads but only such tension forces as would be created by moments tending to separate the stampings.

From the foregoing, it is believed that my invention may be readily understood by those skilled in the art without further description, it being borne in mind that numerous changes may be made in the details disclosed, without departing from the spirit of the invention as set forth in the following claims.

I claim:

1. A socket wrench comprising: a pair of stampings, each stamping including a web element and a transverse flange at least partially circumscribing said web element, said stampings adapted to be superimposed with the end surfaces of said flanges in facewise engagement to form a housing; a spacer member disposed within said housing; the web elements of said stampings being formed with coaxially aligned openings registering with passageways transversely extending through said spacer member, the defining edges of the openings in said webs being inturned to form annular shear-resisting elements received within and engaging the wall surfaces at the opposite ends of the registered passageway; and

elongate means extending through said openings and passageway for securing said stampings together with the spacer member therebetween, said elongate means being free of any shear stresses induced into said stampings through reception of said annular shear resisting elements within the opposite ends of said passageway.

2. A socket wrench, comprising: a pair of stampings, each stamping including a web element and a transverse flange at least partially circumscribing said web element, said stampings adapted to be superimposed with the end surfaces of said flanges in facewise engagement to form a housing; a spacer member disposed within said housing; the web elements of said stampings being formed with coaxially aligned apertures registering with a passageway transversely extending through said spacer member, the defining edges of the apertures in said webs being inturned to form shear-resisting elements received within and engaging the wall surfaces at the opposite ends of said passageway; elongate means extending through said apertures and passageway for securing said stampings together with the spacer member therebetween; each web of said housing being formed with a relatively large circular opening; a hub member having at least one groove coaxially formed therein; at least one of said stampings having an inturned arcuate flange concentric to said opening interfitting with said groove and coacting with the walls thereof for supporting said hub element coaxially of said opening for rotation; a series of ratchet teeth circumferentially formed about said hub; and at least one pawl pivotally carried by said spacer member and spring biased into engagement with said teeth whereby said hub is rotatably driven as said wrench is rotated.

3. A socket wrench comprising: a pair of stampings, each stamping including a web element having an opening therethrough and a transverse flange at least partially circumscribing said web element, said stampings adapted to be superimposed with the end surfaces of said

flanges in facewise engagement to form a housing; a spacer member disposed within said housing; the web elements of said stampings being formed with a plurality of spaced coaxially aligned apertures registering with a passageway transversely extending through said spacer member, the defining edges of said apertures being inturned to form shear resisting elements received within the opposite ends of said passageway; a rivet extending through each of said aligned apertures and the passageway registering therewith for securing said stampings together, with the spacer member therebetween; a hub member; guide means carried by said hub member and coacting with guide means formed integral with at least one web for mounting and supporting said hub member on said housing for rotative movement with the opposite ends thereof projecting through the openings of said webs; a series of ratchet teeth circumferentially formed about said hub; and pawl means pivotally carried by said spacer member and operative to rotatably drive said hub as said wrench is rotated, the forces induced into the hub during use of the wrench being transmitted to the webs of said stampings through said guide means and to the spacer member through the inturned shear resisting elements of said webs.
